UNITED STATES PATENT OFFICE

171,975

PACKAGE MAKING MACHINE

Harry Sigurd Valdemar Järund, Lund, Sweden,
assignor to Hermorion Ltd., Toronto, Ontario,
Canada, a corporation of Canada

Application September 11, 1953, Serial No. 26,763

Term of patent 14 years

(Cl. D55—1)

To all whom it may concern:

Be it known that I, Harry Sigurd Valdemar Järund, a citizen of Sweden, residing at Lund, Sweden, have invented a new, original, and ornamental Design for a Package Making Machine, of which the following is a specification, reference being had to the accompanying drawings, forming a part hereof, and wherein:

Fig. 1 is an elevational view of one side of a package making machine embodying my new design;

Fig. 2 is an elevational view of the opposite side thereof;

Fig. 3 is a front elevation;
Fig. 4 is a rear elevation; and
Fig. 5 is a top plan view of said machine.
I claim:
The ornamental design for a package making machine, as shown.
